ATTORNEY.

UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

DRILLING-MACHINE.

1,372,252.

Specification of Letters Patent. Patented Mar. 22, 1921.

Application filed June 19, 1919. Serial No. 305,301.

To all whom it may concern:

Be it known that I, WILLARD T. SEARS, a citizen of the United States, residing at Montclair, in the county of Essex and State 5 of New Jersey, have invented certain new and useful Improvements in Drilling-Machines, of which the following is a specification.

This invention relates to radial drilling 10 machines of the type in which the saddle is longitudinally movable along the horizontal arm by which it is supported and in which the drill head and spindle are angularly adjustable on the saddle. One object of the 15 invention is to provide an improved mechanism for effecting the movement of the saddle along the arm. In accordance with 20 the invention this mechanism includes a hand wheel normally located in a convenient position such that it incidentally interferes with the angular adjustment of the 25 spindle to certain unusual but occasionally necessary positions. The hand wheel is mounted so that it can be moved, preferably pivotally, so as to permit the required spindle adjustments and nevertheless remain operative although in a less convenient position. By my invention, I also provide 30 certain advantageous structural features of improvement.

In the accompanying drawings I have shown the invention in a preferred form, but it will be understood that it may be otherwise embodied and that the drawings 35 are not to be construed as limiting or defining the scope of the invention, the accompanying claims being relied upon for that purpose.

Of the drawings:

40 Figure 1 is a side view of a radial drilling machine embodying the invention.

Fig. 2 is a sectional view through the line 2—2 of Fig. 1.

45 Fig. 3 is a fragmentary sectional view through the lines 3—3 of Figs. 2 and 4.

Fig. 4 is a sectional view through the line 4—4 of Fig. 2.

The drilling machine shown consists of a main column 1 mounted on a base 2 so as to 50 allow angular movement about a vertical axis. The column consists of two parallel parts which support a carrier frame 3 in such a way as to permit vertical adjustment.

On one side of the frame 3 is secured a 55 casing 4 containing the gearing for speed

control and carrying an electric motor 5. On the opposite side, the arm 6 is secured and a main arm shaft 7 extends longitudinally of the arm. Preferably this arm is angularly adjustable about the axis of the 60 shaft 7.

A saddle 8 is carried by the arm 6 in such a way as to allow longitudinal movement along the arm. A drill head 9 is secured to the saddle 8 and a spindle 10 is rotatably 65 mounted on the head. The spindle is rotated from the shaft 7 in any usual or preferred way and is longitudinally movable to bring it into operative position or to effect feeding.

70 These general features of the machine as thus far described are in no way essential to my present invention and I do not limit myself to this particular form of machine, as the general construction and arrangement 75 of parts may differ widely from that shown.

The drill head 9 is angularly adjustable relative to the saddle 8 about a horizontal axis perpendicular to the axis of shaft 7. A means is provided for controlling this adjustment, preferably consisting of a vertical shaft 11 rotatably mounted on the saddle 8, a worm 12 secured to the shaft and a circular series of gear teeth 13 formed on the head and adapted to mesh with the worm. 80 This construction is fully described in my copending application for drilling machines, Serial No. 206,780 filed December 12th, 1917.

85 Preferably, the arm 6 is provided with two separate guideways 14 and 15 which are 90 out of vertical alinement with each other, the guideway 14 projecting out farther than 15. The saddle 8 is constructed to engage these guideways and the weight of the saddle and the drill head is carried by an anti-friction means such as the inclined rollers 95 16. This construction is set forth in my copending application for saddle and head supporting mechanism for drilling machines, Serial No. 246,859 filed July 20th, 1918. 100

A means for locking the saddle against longitudinal movement along the arm is provided. Preferably this comprises a rear surface 17 of the lower guideway 15 which is engaged by one or more shoes 18 carried 105 by the saddle. The shoe is held in place by a bolt which may be tightened by a hand lever 19 drawing the shoe into firm engagement with the surface 17 and locking the saddle against motion.

A mechanism is provided to enable the operator to easily move the saddle and drill head along the arm, this mechanism comprising a rack 20 secured to the arm 6 and a meshing pinion 21 secured to or formed as a part of a shaft 22. The shaft 22 is rotatably mounted in suitable bearings in the saddle 8 and is approximately vertical, but it may be slightly inclined as shown, the rack being 10 similarly inclined.

For rotating the shaft 22, there is provided a second shaft 23 which is preferably approximately horizontal although it may be inclined so as to be perpendicular to the 15 shaft 22. The shaft 23 is preferably pivotally movable about the axis of the shaft 22 and suitable means is provided for operatively connecting the two shafts. As illustrated, this means consists of two meshing 20 spiral gears 24 and 25. These gears are located in a casing 26 which is movable about the axis of the shaft 22 and which also provides a bearing for the shaft 23. A hand wheel 27 is secured to the shaft 23 for turning 25 it and for thus turning the shaft 22 and moving the saddle. In order to provide for the maximum convenience of the operator, the hand wheel is located in a position such that incidentally it interferes with the angular 30 adjustment of the spindle 10. It will be understood however that in the usual and ordinary operation of the machine the drilling is done with the drill spindle substantially vertical in which position the hand 35 wheel 27 in its most convenient position, illustrated in Figs. 1 and 2, in no way interferes with the operation of the machine.

A means is provided for locking the casing 26 against rotative motion about the axis 40 of the shaft 22. Preferably, this means comprises a flange 28 with a slot 29 cut therein in the arc of a circle with its center on the axis of the shaft 22. A bolt 30 passes through this slot and is threaded to fit into 45 a tapped hole 31 in the saddle. By tightening the bolt, the flange 28 and hence the casing 24 is locked against rotation.

From the foregoing description, it will be seen that shaft 23, the hand wheel 27 secured 50 thereto, the gear 25 and the casing 26 may be pivotally adjusted about the axis of shaft 22. As the axis of the gear 24 is coincident with the axis of rotation, the gears 25 and 24 will remain meshed in operative relation. 55 By means of the bolt 30, the casing and associated parts including the hand wheel may be locked in any one of a number of positions and the mechanism remains operative in all positions.

Ordinarily, the hand wheel is used in the 60 position shown in the drawing which is within easy reach of the operator and greatly more convenient than would be a hand wheel otherwise positioned, as for instance one secured directly to the shaft 22. However,

when it is desired to angularly adjust the drill head in relation to the saddle as previously described, the hand wheel would interfere with movement of the spindle to certain positions. In such cases, the hand wheel 70 may be moved to a position as shown by the dot-and-dash lines of Fig. 2 and locked and operated in that position.

One advantage of this construction is that for the usual operating conditions the hand 75 wheel occupies a position affording the greatest convenience; but when this position interferes with the drill spindle the hand wheel may be temporarily moved to a less convenient but still operative position. 80

What I claim is:

1. In a radial drilling machine, the combination of a horizontal arm, a saddle slidably mounted thereon, mechanism including a hand wheel for moving the saddle along the arm, and means whereby the position of the hand wheel relative to the saddle may be changed without impairing the operativeness of the said mechanism. 85

2. In a radial drilling machine, the combination of a horizontal arm, a saddle slidably mounted thereon, mechanism including a hand wheel for moving the saddle along the arm, and means whereby the hand wheel may be pivotally adjusted to another position relative to the saddle without impairing 95 the operativeness of the said mechanism.

3. In a radial drilling machine, the combination of a horizontal arm, a saddle slidably mounted thereon, mechanism including a hand wheel for moving the saddle along the arm, means whereby the position of the hand wheel relative to the saddle may be changed without impairing the operativeness of the said mechanism, and a device for 100 locking the hand wheel in its adjusted position. 105

4. In a radial drilling machine, the combination of a horizontal arm, a saddle slidably mounted thereon, mechanism for moving the saddle along the arm including a hand wheel, two rotatably mounted and operatively connected shafts, means whereby the hand wheel is fixedly mounted on one shaft and pivotally adjustable to different 110 positions about the axis of the second shaft, and an operative connection between the second shaft and the arm. 115

5. In a radial drilling machine, the combination of a horizontal arm, a saddle slidably mounted thereon, mechanism for moving the saddle along the arm including two rotatably mounted shafts, a spiral gear on one shaft, a bracket surrounding such shaft and spiral gear and supporting the second 120 shaft with a spiral gear thereon in mesh with the first spiral gear, a hand wheel on the second shaft, the bracket being adjustable about the first shaft and spiral gear, means for locking the bracket in adjusted 125 130

position, and an operative connection between the second shaft and the arm.

6. In a radial drilling machine, the combination of a horizontal arm, a saddle slidably mounted thereon, mechanism for moving the saddle along the arm including a hand wheel, two rotatably mounted and operatively connected shafts, means whereby the hand wheel is fixedly mounted on one shaft and pivotally adjustable to different positions about the axis of the second shaft, a pinion secured to said second shaft, and a rack secured to the arm and meshing with the pinion.

15 7. In a radial drilling machine, the combination of a horizontal arm, a saddle slidably mounted thereon, a drill head on the saddle and angularly adjustable therewith about a horizontal axis, a spindle rotatably mounted on the head, mechanism for moving the saddle along the arm comprising two rotatably mounted shafts, a hand wheel, and means whereby the position thereof relative to the saddle may be changed in order to avoid interference between the hand wheel and the spindle which certain positions of the head would otherwise cause.

8. In a radial drilling machine, the combination of a horizontal arm, a saddle slidably mounted thereon, a drill head on the saddle and angularly adjustable therewith about a horizontal axis, a spindle rotatably mounted on the head, mechanism for moving the saddle along the arm comprising a hand wheel normally in a position in the path of the spindle when the latter is adjusted angularly, and means whereby the hand wheel may be moved out of the said path and nevertheless remain operative.

40 9. In a radial drilling machine, the combination of a horizontal arm, a saddle slidably mounted thereon, a drill head on the saddle and angularly adjustable therewith about a horizontal axis, a spindle rotatably

mounted on the head, mechanism for moving the saddle along the arm comprising a hand wheel normally in a position in the path of the spindle when the latter is adjusted angularly, means whereby the hand wheel may be pivotally adjusted to another position out of the said path and nevertheless remain operative, and means for locking the hand wheel in its adjusted position.

10. In a radial drilling machine, the combination of a horizontal arm, a saddle slidably mounted thereon, a drill head on the saddle and angularly adjustable therewith about a horizontal axis, a spindle rotatably mounted on the head, mechanism for moving the saddle along the arm comprising a hand wheel normally in a position in the path of the spindle when the latter is adjusted angularly and normally having its axis horizontal and perpendicular to the arm approximately, and means whereby the hand wheel may be pivotally moved about an approximately vertical axis out of the said path.

11. In a radial drilling machine, the combination of a horizontal arm, a saddle slidably mounted thereon, a drill head on the saddle and angularly adjustable therewith about a horizontal axis, a spindle rotatably mounted on the head, mechanism for moving the saddle along the arm comprising a hand wheel, an approximately vertical shaft, an approximately horizontal shaft normally perpendicular to the arm, spiral gears connecting the two shafts and a hand wheel on the front end of the second shaft normally in a position in the path of the spindle when the latter is adjusted angularly, and means whereby the hand wheel may be moved about the axis of the first shaft out of the said path and nevertheless remain operative.

In testimony whereof I hereto affix my signature.

WILLARD T. SEARS.
